UNITED STATES PATENT OFFICE

140,574

DESIGN FOR A COMBINED SINK AND CABINET

Jacques Stanitz, Warren, Ohio, assignor to
Mullins Manufacturing Corporation, Salem,
Ohio, a corporation of New York

Application December 9, 1944, Serial No. 116,803

Term of patent 7 years

(Cl. D4—2)

To all whom it may concern:

Be it known that I, Jacques Stanitz, a citizen of the United States, residing at Warren, in the county of Trumbull and State of Ohio, have invented a new, original, and ornamental Design for a Combined Sink and Cabinet, of which the following is a specification, reference being had to the accompanying drawing, forming part thereof.

The figure is a perspective view of a combined

sink and cabinet for a kitchen showing my new design; the rear, not shown, presenting substantially a plane surface.

The characteristic features of my design are shown by means of full lines in the drawing.

I claim:

The ornamental design for a combined sink and cabinet, substantially as shown and described.

JACQUES STANITZ.
